UNITED STATES PATENT OFFICE.

FRANCIS C. KOLLATH AND EDWARD M. SCHOENING, OF CHICAGO, ILLINOIS.

LAMP AND GUARD HANDLE.

Application filed November 17, 1923. Serial No. 675,276.

To all whom it may concern:

Be it known that we, FRANCIS C. KOLLATH and EDWARD M. SCHOENING, citizens of the United States, residing at Chicago, in the 5 county of Cook and State of Illinois, have invented a certain new and useful Improvement in Lamps and Guard Handles, of which the following is a specification.

Our invention relates to handles for electric lamps and lamp guards, especially of that type wherein the handle is composed of flexible rubber. The general object of the invention is to provide a device of this character which shall be easily operated, durable, 10 and capable of securely holding the lamp and guard in proper relation to each other and to the handle. One of the specific objects of the invention is to provide an internal collar near the forward end designed 15 to enter the groove in the socket for retaining the latter in place. Another object is to provide an annular groove or depression at the same point on the handle, but on the outside, for receiving a clamping ring which 20 when in position will prevent the socket from being withdrawn. Still another object is to provide a handle in which the socket receiving chamber is elongated toward the rear for accommodating a knot in 25 the electric conductor. It is also our purpose to form a shoulder at the inner end of 30 this chamber to form a stop against which the knot may abut, thus relieving the socket of any rearward strain on the electric conductors. Still another object is to so form 35 the passage at the rear of the handle that adhesive tape, wound around the conductors, may be accommodated.

We accomplish our objects by the construction illustrated in the accompanying drawing in which—

Figure 1 is a side view of the complete device showing a lamp in position.

Figure 2 is an enlarged view of the parts shown in Figure 1, the handle being shown in axial section.

Figure 3 is an axial section of the handle alone; and

Figure 4 is a perspective view of a standard type of socket suitable for use with our handle.

Like numerals denote like parts throughout the several views.

The handle itself consists of a single piece 55 of flexible rubber and by "flexible" we mean

rubber which is resilient and comparatively soft so that it may bend and stretch within reasonable limits and form a cushion for absorbing any shocks and jars which may occur incidentally to use in a shop or factory. This handle consists of a forward section 1 and a butt or rear section 2. The butt is comparatively thick so that it may afford a firm and easy grip for the user. It has a longitudinal passage 3 for accommodating the electric conductors 4. This passage is enlarged at the point 6 for accommodating the adhesive tape 7 which in practice may be wrapped around the conductors.

At the forward portion the handle has a chamber 10 near the mouth of which is an internal collar 12 adapted to fit into a corresponding annular groove 14 in the lamp socket 15. This lamp socket is of known design and hence need not be described except to say that it is internally threaded near the forward end for receiving the threaded butt of a lamp bulb 16. The conductors 4 pass out through the rear end of the socket in 70 the usual manner.

Chamber 10 is elongated at the inner end in the sense of being longer than the socket, the purpose being to accommodate a knot 18 formed in the conductors behind the socket. 75 A shoulder 20 is formed at the junction of the chamber 10 and portion 6 of the passage 3. This shoulder is annular and forms an abutment against which the knot may seat when tension is exerted on the conductors in 80 a rearward direction.

Directly outside of the internal collar 12 is an annular channel or groove 22 for accommodating a clamping ring 24. This ring is a so-called "split ring", the ends of 85 which may be secured by a screw 26 as shown in Figure 1. When this ring is clamped in place it holds the collar 12 firmly seated in the groove 14 of the socket, thus preventing the latter from being withdrawn 100 and holding it firmly in place. While this clamping ring may be a separate piece it will ordinarily form part of a lamp guard 30 made of wire and forming a cage around the lamp in the usual manner.

In practice, when the parts are assembled as shown in Figures 1 and 2 the rubber performs the dual function of cushioning the lamp to prevent breakage of the filament and a convenient handle by which the lamp 105 110

may be manipulated. When the clamping ring 24 is in position the socket and lamp will be firmly held and the socket cannot be withdrawn from the handle, but when the 5 ring is removed the socket may be removed by merely exerting an outward pull. As the rubber is resilient the collar 12 will yield and permit the socket to be withdrawn.

The shoulder 20 performs a useful function in forming an abutment for the knot 18. It often happens in practice that the conductors will be jerked backward, but when this happens with our device the knot in the conductors will seat against the shoulder 15 and prevent any strain from reaching the socket or the devices by which the socket is secured to the conductors.

From the foregoing it will be evident that our device is simple to manufacture and 20 yet is extremely practical and efficient in use.

Having thus described our invention what we claim as new and desire to secure by Letters Patent is:

- 25 1. A handle for portable electric lamps and guards, consisting of a single piece of flexible rubber having a chamber for accommodating the lamp socket, and a passage of reduced diameter extending from said chamber to the rear end of the handle for accommodating the electric conductors, the handle having an internal collar near its forward end and a corresponding annular depression on the outside, the collar for retaining the 30 lamp socket and the depression for accom-

modating a clamping ring for holding the collar to its work.

2. A one-piece rubber handle for electric lamps, consisting of flexible rubber having a chamber for accommodating the lamp 40 socket and a passage of reduced diameter extending rearward from the said chamber for accommodating the electric conductors, the handle having an internal collar near its forward end for retaining the socket in position, said chamber being axially elongated for accommodating a knot in the conductors, there being a shoulder formed at the junction of the chamber and passage to form an abutment for the knot to thereby relieve the 50 socket of any strain on the conductors.

3. A lamp and guard handle consisting of a single piece of flexible rubber having a chamber of large diameter for accommodating the lamp socket, and a passage extending rearward from said chamber for accommodating the electric conductors, the forward end of the passage being larger than the rear end for accommodating binding tape around the conductors, and means 60 for holding the socket near the forward end of the handle, the chamber being axially elongated at the inner end for accommodating a knot in the conductors behind the 65 socket.

In witness whereof, we have hereunto subscribed our names.

FRANCIS C. KOLLATH.
EDWARD M. SCHOENING.
